DESIGN FOR WALL-PAPER.

SPECIFICATION forming part of Design No. 21,948, dated November 1, 1892.

Application filed October 3, 1892. Serial No. 447,733. Term of patent 8½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part thereof.

10 The leading feature of this design consists of an ornament of the rococo style, composed of three connected ornamental scrolls which extend from a cornucopia-like base, with a flower in the center of the three scrolls and a 15 small festoon of flowers hanging over the base

of the ornament, as represented in the accompanying drawing.

The design is placed at regular intervals over the surface of the paper and is printed in any desired color or colors or in bronze 20 and colors.

What I claim is—

The design for wall-paper herein shown and described.

Witness my hand this 30th day of September, 1892.

CHARLES BOOZE.
